UNITED STATES PATENT OFFICE.

HARRY E. KATZENMOYER, OF READING, PENNSYLVANIA, ASSIGNOR TO SCOTT AND WILLIAMS, INC., OF NEW YORK, N. Y., A CORPORATION OF MASSACHUSETTS.

CIRCULAR-KNITTING MACHINE.

Application filed October 17, 1923. Serial No. 669,094.

The main object of my invention is to so construct circular knitting machines that varied constructions and designs of knitted products can be obtained by the making of structural changes in the knitting, as for example by the employment of tuck stitches. My invention is particularly useful in the knitting of hosiery, where it is desired to produce "clock" effects in the sides of the stockings by such variations in the knitting as is obtained by the use of tuck stitches for the line of "clocking." In the accompanying drawings I have illustrated my invention as employed in the construction of a circular knitting machine for the knitting of seamless hosiery in which there are produced tuck stitches to imitate the narrowing marks at the calf of the leg and also other tuck stitches to produce the appearance of clocks at the sides of the leg and foot of the stocking.

In the accompanying drawings:

Fig. 1 is a diagram of the needle controlling cams extended.

Fig. 2 illustrates the different types of needles employed.

Fig. 3 is a sectional plan view of the bed of the knitting machine, without the cylinder, but showing the locations of the three clearing cams for the needles.

Fig. 4 is a partial side elevation showing one of the clearing cams:

Fig. 5 is a view of a detail:

Fig. 6 is a view of another detail on a much larger scale:

Fig. 7 is a rear elevation of part of the machine showing certain of the cam controlling devices which are hereinafter described:

Fig. 8 is a front elevation of part of the mechanism:

Fig. 9 is a diagram illustrating a type of stocking which may be produced on my machine.

Referring to this Fig. 9, illustrating a woman's stocking, the marks α indicate the lines of spaced tuck stitches formed at the calf of the leg of the stocking on each side of and parallel with the back seam γ in imitation of the narrowing marks of what is commonly termed a full fashioned stocking.

At α in this Fig. 9 I have indicated clocking effects to be produced at the sides of the stocking by lines of tuck stitches. The number of the lines of tuck stitches may be va-

ried in each stocking to add to the ornamental effect. For example, there may be four lines of tuck stitches throughout most of the length of the clocking even along the foot, while for a short distance near the top as at α' , there may be but two lines of such tuck stitches.

My present invention provides means whereby the above and other varied effects may be produced by tucking, especially where the knitting has to be varied in successive courses.

In carrying out my invention I do not restrict myself to any particular tucking means, but I find it convenient to make use of four styles of knitting needles, two with latches of ordinary length, or as we may call them "short" latches and two with long latches. The short latch needles n and n' , Fig. 2, are for producing the ordinary knitting at wales where there is to be no tucking. These needles are as usual in two groups, one group n having long butts constituting the instep needles and the other group n' having short butts for the rest of the circle of needles, except where long latch tucking needles are intercalated in either of the groups of short latch needles. Of the long latch needles, one form n^2 has a long butt, while the other form n^3 has an extra long butt, as shown in Fig. 2.

The needles n^2 are introduced into the group of needles at the two wales in which the tuck stitches α (Fig. 9) are to be intermittently formed and also at those wales of the clocking α where the lines of tuck stitches are continuous throughout the length of the clocking. Where any of the lines of tuck stitches for clocking are to be interrupted, as in the outer rows at α' Fig. 9, I use the needles n^3 , which have the extra long butts.

To produce tuck stitching by the aid of the long latch needles, I prefer to employ mechanism of the same general construction as that which forms the subject of my Patent 1,404,124 dated January 17, 1922, including the use of a movable clearing cam 50, (Fig. 1), pivoted at 51 and having at its free end a pin 52 projecting to the exterior of the cam cylinder 53, Fig. 3, and controlled from the pattern chain, as described in my said patent.

This pin 52, as seen in Fig. 3, rests upon the outer end of a lever 49 pivoted at 48 to a suitable bracket on the bed plate 10 of

the machine, and connected at its other end to a rod 47 which is vertically guided in the bed plate with its lower end immediately over a rotatable cam 8, Figs. 6, 7 and 8.

- 5 When the rod 47 is not held in an elevated position by this cam 8, this rod will stay in its lower position by gravity, resting upon the hub of the cam, as shown in Figs. 6 and 7, and will elevate the end of the lever 49, 10 which supports the free end of the switch cam 50 to keep the latter in its higher position shown by dotted lines in Fig. 1. When this cam 50 is held in that position, all the long latch needles as well as the short latch 15 needles will be projected far enough to clear their stitches. But when the cam 8 in its rotation, raises the rod 47, the cam 50 will drop to the position shown by full lines in Fig. 1, where the long latch needles will not 20 be projected far enough to clear the loops, but the short latch needles will clear them.

The above mentioned controlling cam 8 like the similar cam 8 of my above mentioned patent is mounted to turn upon a stud 25 5 carried by a bracket 4, which is secured to the frame 1 of the machine. The cam is intermittently rotated by means of a ratchet wheel 6 which is secured to the cam and which may be actuated and controlled by 30 mechanism such as is fully set forth in my above mentioned patent and forms no essential part of my present invention.

This cam 8 in my present invention has 35 two diametrically opposite acting faces 9, 9, instead of one as in my former patent, to lift the rod 47, and the ratchet wheel 6 is in the present instance provided with eight teeth so that when the tucking is to take place, as described in my former patent, the result with this modified construction of cam 40 is to have the cam 50 elevated for say two courses and lowered for say two courses alternately. This action produces the preferred arrangement of tucking where the 45 clocking effect is desired. At the part of the stocking where the imitation narrowing marks α are to be introduced, these marks should be spaced apart more than two courses, so I provide an additional clearing cam 60, Figs. 1, 3 and 4, to intermittently 50 act upon the needles n^2 , in the narrowing mark wales at the two courses where tuck stitches are not required at those narrowing mark wales. In other words, at those two 55 courses the clearing cam 60 will have the effect to obliterate, as it were, the tuck stitches which would have been produced by the action of the cam 50 on those particular needles.

60 This additional clearing cam 60 is shown as pivoted in a notch in upper edge of the cam ring 53, Figs. 1, 3 and 4, and I provide means whereby this cam 60 is raised to its elevated active clearing position only 65 during that part of the revolution of the

knitting head while the two needles which are to form the narrowing marks are passing this cam 60. For this purpose I may mount a slotted slide bar 62 on guide pins 63 on the face of the bed plate 10, Fig. 3, 70 to act upon a finger 61 on the pivoted cam 60. This slide bar 62 is drawn in one direction by a pull spring 62' and at its outer end is acted on by a pin 64 on the horizontal lever 65, which is pivoted on a vertical axis 75 at 66, Fig. 3, and has an arm 67 hinged to the lever 65 by a horizontal hinge 68 so that this arm 67 can be raised out of or depressed into the path of a pendent swinging lever 59 pivoted at 58 to the side of the frame 1 80 of the machine as shown in Fig. 5. This lever 59 is acted on at each revolution of the knitting head by one or other of the cams 56 on the revolving wheel 55, so that if the arm 67 is in line with the striking projection 85 54 on the lever 59 (as shown by full lines in Fig. 5) the lever 65 (Fig. 3) will be caused to push the slide rod 62 so as to raise the cam 60 at the proper moment to clear the loops on those two needles n^2 which are 90 in the narrowing mark wales.

Means are provided for doing this for say two successive courses and then for intermitting the action for say two successive courses. This latter effect is obtained by the 95 provision of means to automatically raise the hinged arm 67 to the dotted position, Figs. 5 and 8, so that the lever 65 will not then be acted on by the constantly oscillating lever 59.

This arm 67 is guided in a pair of fingers 71 on a vertical rod 72 whose lower end may be connected to a lever 73 pivoted to the frame at 74, while its upper end passes through and is guided in a hole in the plate 100 1 of the frame. A pull spring 70 tends to draw this rod 72 and the arm 67 to the upper position.

To depress the rod 72 and arm 67 to the lower position with the arm 67 in line with 110 the projection 54 on the swinging lever 59, I provide a lever 75 on a horizontal pivot 76 on the plate 1. Under the outer end of this lever 75 is a pin 77 guided vertically in the bed plate 10, and resting at its lower end 115 upon a cam 78 or the hub thereof, which lies between, and is attached to, the ratchet 6 and cam 8. When the pin 77 rests upon the cam 78, as seen in Figs. 6 and 7, the lever 75 is tilted to depress the rod 72 (Figs. 7 120 and 8) to bring the arm 67 for the time being into the path of the oscillating lever 59 to raise the clearing cam 60 into operative position for a part of each of the two or other desired number of revolutions of the 125 knitting head.

A pull spring 79 may be employed to tend to draw down that end of the lever 75 which is acted on by the pin 77.

In the present instance, I have shown my 130

invention as applied to a knitting machine with a revolving needle cylinder and non-revolving cam cylinder, but my improvements may be applied to other makes of circular knitting machines.

5 A further feature of my invention relates to the means whereby the clocking may be made of different widths. For this purpose I provide a third clearing cam 80 (Figs. 1 10 and 3), which may be brought into action at the courses where it is desired to reduce the number of lines of tuck stitches and so reduce the width of the clocking effect as indicated at z' Fig. 9.

15 At those wales where the tucking is to be temporarily stopped (in the case indicated at z' it is the outer wales of the clocking) I employ needles n^3 , (Fig. 2) with extra long butts and this third clearing cam 80 is moved 20 radially inwards at the appropriate courses sufficiently far, and only sufficiently far, to act upon the butts of these needles n^3 to make them clear their loops, but not to act upon the butts of any of the other needles. 25 Similarly, if it is desired to make the intermittent tuck stitches x without the clocking z or z' needles having long latches like the needles n^3 or n^2 and regular short butts like needles n' are employed, where the intermittent 30 tuck x is desired and the clearing cam 80 is inserted sufficiently to clear the needles n^2 and n^3 .

To move this cam 80 inward I may use devices such as described in Scott's Patent 35 1,152,850, September 7, 1915, for controlling radially movable cams. Thus I may provide a suitable cam 20 on the pattern drum 120 to act upon an upright thrust bar 460 with a cam 485 (Fig. 3) which when the thrust bar 40 is raised as described in said Scott's patent operates a lever 487, pivoted at 488 on the table 1 and acting at its other end (Fig. 3) upon the outer end of the radially guided cam 80.

45 A further feature of my invention is to so construct the machine as to make sure that the tucking cam 50 will be maintained in its elevated clearing position (shown by dotted lines in Fig. 1) during the knitting of the 50 heel and toe pockets. For this purpose, I connect to the outer end of the lever 49, Fig. 8, a wire 81 whose lower end is connected to a lever 82, pivoted at 83 to the

frame and having its free end in the path of a pin 84 on the clutch shifter 85, so that 55 when the clutch is shifted to the left, that is from the round and round knitting to the reciprocating knitting position of the machine this pin 84 will raise the free end of this lever 82 and depress its other end to pull 60 down the connected end of lever 49 and so keep the cam 50 raised to the clearing position, Fig. 1, during reciprocating knitting.

I claim as my invention—

1. A circular knitting machine having 65 needles some of which have long butts and others short butts and a movable clearing cam therefor and means for moving this cam either to the clearing or the tucking position in combination with an additional clearing 70 cam and automatic means to move the latter to active position during a part only of a revolution, as and for the purpose set forth.

2. A circular knitting machine having 75 needles some of which have long butts and others short butts and a movable clearing cam therefor and means for moving this cam either to the clearing or the tucking position in combination with an additional clearing 80 cam and automatic means to move the latter to its active position during a part only of each revolution for successive revolutions.

3. A circular knitting machine having 85 long and short latch needles some with long butts and others with short butts and a movable clearing cam therefor and means for moving this cam either to the clearing or the tucking position in combination with an additional clearing cam and automatic 90 means to move the latter to active position during a part only of a revolution, as and for the purpose set forth.

4. A circular knitting machine having 95 long and short latch needles some with long butts and others with short butts and a movable clearing cam therefor and means for moving this cam either to the clearing or the tucking position in combination with an additional clearing cam and automatic means to move the latter to its active position 100 during a part only of each revolution for successive revolutions.

In testimony whereof I have signed my name to this specification.

HARRY E. KATZENMOYER.
